CLAIM

The ornamental design for a circular container with ridged lid, as shown and described.

DESCRIPTION

FIG. 1 is a top perspective view of a circular container with rigid lid showing my new design;

FIG. 2 is an exploded top perspective view thereof;

FIG. 3 is a top plan view thereof;

FIG. 4 is a side elevation view thereof; and,

FIG. 5 is a partial cross-section view taken along the line 5—5 in FIG. 4 showing the gasket detail inside the lid portion, shown on an enlarged scale.
